EXTRUSION MILL AND FEEDER MEANS
THEREFOR

James T. Keefe, San Carlos, Calif., assignor to California Pellet Mill Company, San Francisco, Calif., a corporation of California
Continuation of application Ser. No. 773,440, Nov. 12, 1958. This application Sept. 10, 1962, Ser. No. 223,577
6 Claims. (Cl. 18—12)

The invention relates to extrusion mills and more particularly to the type utilized in the pelletizing of moldable material. This application is a continuation of my pending application for Extrusion Mill and Feeder Means Therefor, Serial No. 773,440, filed Nov. 12, 1958, now abandoned.

One of the problems connected with the operation of such a mill is to, not only assure substantially equal rate of feed of the moldable material to each of the extrusion rollers conventionally employed in such a mill, but also to assure maximum feed to such rollers commensurate with the capacity of the rollers to extrude the material fed to them, whereby to obtain both a maximum and uniform output from the mill. This is particularly important with respect to light weight, bulky materials, as such materials are rather difficult to handle in connection with the extrusion of the same, and present a real problem in the extrusion thereof.

One manner of attaching this problem is to pre-compact the light weight bulky material at some point prior to its reaching the extrusion roller, whereby the material will more nearly approach the more compact type of material which the rollers have no difficulty in extruding through the die to produce firm pellets.

Among the objects of the present invention are:

(1) To provide a novel and improved extrusion mill capable of producing firm extrusions from moldable material which is normally of light weight and bulky;

(2) To provide a novel and improved extrusion mill capable of precompacting material which is normally of light weight and bulky, to subsequently effect firm extrusions of such material;

(3) To provide novel and improved feed means for an extrusion mill of the above type, which will increase the output of such mill and improve the efficiency thereof, particularly in the handling of light weight, bulky material; and

(4) To provide novel and improved feed means for an extrusion mill of the above type, which feed means may be adjusted to the character of material fed to such mill.

Additional objects of the invention will be brought out in the following description of a preferred embodiment of the same, taken in conjunction with the accompanying drawings, wherein,

FIG. 1 is a front view in elevation of an extrusion mill embodying the present invention, showing the mill with its door in closed position;

FIG. 2 is a view in section taken in the plane 2—2 of FIG. 1; and

FIG. 3 is a front view in elevation with the door of the mill in open position.

Referring to the drawings for details of the present invention, the same is disclosed as embodied in a mill of the type illustrated in Meakin patent for Extrusion Mill, No. 2,240,660 of May 6, 1941, and insofar as the present invention is concerned, such mill involves a mill housing 1 having a front wall 3 adjacent which is rotatably supported, a cylindrical die 5 with its longitudinal axis normal to the front wall of the housing, to provide a die chamber 7.

Located within the die chamber are a pair of extrusion means such as rollers 9 for cooperating with the cylindri-

2

cal die in the extrusion of moldable material through the die holes. These rollers are mounted within a horizontally disposed cage comprising a front end plate 11 and a rear end plate 13, the cage serving to carry the spindles on

5 which the rollers revolve.

Hingedly secured to the mill housing by a pair of hinge brackets 15 is a door 17 including a substantially cylindrical wall 19 of a diameter exceeding that of said die and having alternative discharge passageways 21, 23 at its lowermost point controlled by a flap gate 25, and a front wall 27 spanning an end of said substantially cylindrical wall, this front wall having a feed opening 30 therein.

10 Mounted on the inner surface of the front wall of the door, and concentric with the feed opening therein, is a ring shaped element 31 having an inside conical surface 33 flaring inwardly. With the door in its closed position, this ring is concentric with the die, and in spaced relationship thereto.

15 In the space intermediate the die 5 and the ring element 31, there is mounted a feeder blade assembly involving a mounting ring 35 including an intermediate section 37, an outwardly directed mounting flange 39 at one end of the intermediate section and an inwardly directed feeder blade attaching flange 41 at the other end of the intermediate section, the internal diameter of flange 41 matching the diameter at the large end of the conical surface 33.

20 To the inner edge of this blade attaching flange 41 are welded one or more feeder blades 43, preferably a plurality of the same uniformly spaced about the circumference.

25 The feeder blade assembly is affixed to the free end of the die, for which purpose the die is grooved adjacent its front end to provide a rib 45 for use with a chain clamp 47 in which alternate trough type links 48 straddle the flange 39 and rib 45 about the die, and when tensioned, serves to

30 clamp the blade assembly to the end of the die.

35 The blade supporting flange 41 is provided with a frontal rib 51 adapted to fit a complementary groove in the facing end of the ring element 31 when the door is swung to its closed position. The door is held in such closed position by eye bolt arrangements 52 or suitable means.

40 The feeder blades 43 are mounted on a helical or spiral pattern, their disposition being such that with the door in its closed condition, one edge of each blade will lie along and in close proximity to the inwardly flaring conical surface 33 of the ring 31.

45 It will be appreciated from the foregoing construction, that the feeder blade assembly, being affixed to the die, will whirl with the die, while the ring with the conical surface remains fixed. Moldable material, therefore, entering the feed opening in the door, will be engaged by the whirling blades, and by reason of the helical or spiral pattern of these blades, such material will be whirled with considerable velocity into the die chamber, in the course of which, the upper half of the die chamber will receive a substantial portion of the incoming material.

50 The large increase in velocity thus imparted to the material as it approaches the die chamber, effectively increases the volume of material capable of being handled by the mill, which therefore calls for a door opening of a diameter somewhat in excess of openings conventionally provided in prior art machines employing dies of similar size, to accommodate such increase, and along with this, a hopper discharge chute 61 of correspondingly increased cross sectional dimensions.

55 Such chute, when swung away from the door exposes the feed opening in the door, which because of its increased size, permits access to the interior of the mill to allow certain cleaning and servicing operations without the necessity of unbolting and opening the door. This advantage was not readily available in machines of similar type, which did not embody the present invention.

That portion of the incoming material which is directed by the whirling blades toward the lower half of the die chamber is aided by gravity in its movement toward this portion of the die chamber. That portion of the material however which is thrown upwardly by the whirling blades, is not aided by the force of gravity, and to encourage a fuller measure of flow of material into the upper half of the die chamber, one might provide a baffle 65 at the upper end of a post 67 which is anchored in the roller cage, the baffle being of a length to extend from the inwardly directed flange 41 of the blade assembly, to a point within the die chamber, and having its upper edge arced to conform to the curvature of the die 5 and the mounting ring 35 of the blade assembly.

With such baffle installed, some of the material thrown upward by the whirling blades, which might ordinarily escape entering the upper half of the die chamber, will strike the baffle and be diverted thereby into the die chamber toward the upper extrusion pocket formed by one of the rollers with the upper half of the die. The baffle is preferably made adjustable as to angularity so that the extent to which it might function may be varied, to realize maximum effectiveness and efficiency for different materials.

The increase in capacity of the machine made possible by the whirling blades, makes the machine very effective in the handling of moldable material which is light in weight and bulky, for the increased rate of feed of such material causes the same to pack itself into the die chamber and bring about a precompaction before extrusion, thereby solving a real problem in connection with the extrusion of light weight and bulky materials.

From the foregoing description of the present invention in its preferred form, it will be apparent that the same is subject to alteration and modification without departing from the underlying principles involved, and I accordingly do not desire to be limited in my protection to the specific details illustrated and described except as may be necessitated by the appended claims.

I claim:

1. An extrusion mill having a cylindrical die rotatably supported with its axis substantially horizontal to provide a die chamber, extrusion means within said cylindrical die, means enclosing said die and having a feed opening therein, means providing a conical surface affixed to and flaring inwardly from said die enclosing means, substantially concentric with the feed opening therein, and with said inwardly flaring conical surface in substantially axial alignment with said die, a feeder blade assembly including a plurality of blades arranged on a circle concentric with the free end of said die, with each blade directed spirally along and in proximity to but out of contact with said inwardly flaring conical surface, and means for rotating said feeder blade assembly relative to said conical surface during rotation of said die to throw material from said conical surface into said cylindrical die between the internal periphery thereof and said extrusion means.

2. An extrusion mill comprising a mill housing, a cylindrical die rotatably supported with one end adjacent said housing and with its axis substantially horizontal to provide a die chamber, extrusion means within said cylindrical die, means enclosing said die and having a feed opening therein, means providing a conical surface affixed to and flaring inwardly from said die enclosing means, and with said inwardly flaring conical surface in substantially axial alignment with said die, a feeder blade assembly intermediate said die and said conical surface means and including at least one blade directed spirally along and in proximity to but out of contact with said inwardly flaring conical surface, and means for rotating said feeder blade assembly relative to said conical surface during rotation of said die to throw material from said conical surface into said cylindrical die between the internal periphery thereof and said extrusion means.

3. An extrusion mill comprising a mill housing having a front wall, a cylindrical die rotatably supported with one end adjacent said housing front wall and with its axis substantially horizontal to provide a die chamber, extrusion means within said cylindrical die, means enclosing said die and having a feed opening therein, means providing a conical surface affixed to and flaring inwardly from said die enclosing means, substantially concentric with the feed opening therein and with said inwardly flaring conical surface in substantially axial alignment with said die, a feeder blade assembly including a plurality of blades arranged on a circle concentric with the free end of said die, with each blade directed spirally along and in proximity to but out of contact with said inwardly flaring conical surface, and means for rotating said feeder blade assembly relative to said conical surface during rotation of said die to throw material from said conical surface into said cylindrical die between the internal periphery thereof and said extrusion means.

4. An extrusion mill comprising a mill housing having a front wall, a cylindrical die rotatably supported with one end adjacent said housing front wall and with its axis substantially horizontal to provide a die chamber, extrusion means within said cylindrical die, a door having a feed opening therein, means providing a conical surface affixed to and flaring inwardly from the front wall of said door substantially concentric with the feed opening therein, means securing said door to said mill housing for closure thereof about said cylindrical die and with said inwardly flaring conical surface in substantially axial alignment with said die, a feeder blade assembly including a plurality of blades arranged on a circle concentric with the free end of said die, with each blade directed spirally along and in proximity to but out of contact with said inwardly flaring conical surface when said door is in its closed position, and means for rotating said feeder blade assembly relative to said conical surface during rotation of said die to throw material from said conical surface into said cylindrical die between the internal periphery thereof and said extrusion means.

5. An extrusion mill comprising a mill housing having a front wall, a cylindrical die rotatably supported with one end adjacent to said housing front wall and with its axis substantially horizontal to provide a die chamber, extrusion means within said cylindrical die, a door including a substantially cylindrical wall of a diameter exceeding that of said die and having a discharge passage, a front wall spanning an end of said substantially cylindrical wall and having a feed opening therein, means providing a conical surface flaring inwardly from the front wall of said door substantially concentric with the feed opening therein, means hingedly securing said door to said mill housing for closure thereof about said cylindrical die and with said inwardly flaring conical surface in substantially axial alignment with said die, a feeder blade assembly including a plurality of blades arranged on a circle concentric with the free end of said die, with each blade directed spirally along and in proximity to said inwardly flaring conical surface when said door is in its closed position, and means for rotating said feeder blade assembly during rotation of said die to throw material from said conical surface into said cylindrical die between the internal periphery thereof and said extrusion means, and means supported in the path of flow of such material into the upper portion of said die chamber for deflecting additional of such material into the upper region of said die chamber.

6. An extrusion mill comprising a mill housing having a front wall, a cylindrical die rotatably supported with one end adjacent said housing front wall and with its axis substantially horizontal to provide a die chamber, extrusion means within said cylindrical die, a door including a substantially cylindrical wall of a diameter exceeding that of said die and having a discharge passage at its lowermost point, a front wall spanning an end of said

substantially cylindrical wall and having a feed opening therein, means providing a conical surface flaring inwardly from the front wall of said door substantially concentric with the feed opening therein, means hingedly securing said door to said mill housing for closure thereof of about said cylindrical die and with said inwardly flaring conical surface in substantially axial alignment with said die, a feeder blade assembly including a plurality of blades arranged on a circle concentric with the free end of said die, with each blade directed spirally along and in proximity to said inwardly flaring conical surface when said door is in its closed position, and means for rotating said feeder blade assembly during rotation of said die to throw material from said conical surface into said cylin-

drical die between the internal periphery thereof and said extrusion means, means supported in the path of flow of such material into the upper portion of said die chamber for deflecting additional of such material into the upper region of said die chamber, said deflecting means including a post extending upwardly from said extrusion assembly and a deflector strip at the upper end of said post, said deflector strip being angularly adjustable to adjust the rate of feed of material to said upper region.
